APPARATUS FOR PACKAGING RESILIENT MATERIAL

Crosby Field, Brooklyn, N. Y., assignor to Brillo Manufacturing Company, Brooklyn, N. Y., a corporation of New York

Application June 16, 1928, Serial No. 285,931
Renewed March 13, 1933

33 Claims. (Cl. 226—101)

This invention relates to apparatus for packaging resilient matted material and has for an object the provision of mechanism which will compact and package such material without undesirably affecting the useful qualities of the material.

The invention has been developed in connection with the packaging of steel wool and will be particularly described in this connection but with 10 the explicit reservation that it is entirely suitable for packaging many other materials of a similar nature, such for example, as metal wool, wood shavings, cotton wool and hair.

It is highly desirable from the consumers' viewpoint that steel wool and similar materials when received for use shall be in a fluffy resilient condition and free from sharp bends. It is equally desirable from the manufacturers' and shippers' viewpoint that such material shall be packed in 20 the smallest possible packages to avoid undue bulk in handling and storing. The usual box and plunger presses do not fulfill these requirements, for though capable of compressing the material to any desired extent they produce numerous sharp bends and to a large extent destroy 25 its resiliency and fluffiness. To avoid this it has become an extensive practice to roll the material by hand to compact it in preparation for packaging, which obviously is slow as well as injurious 30 to the hands of the workers.

The apparatus herein to be described simulates the approved hand packing and additionally furnishes all the advantages of machine practice.

35 Other objects and advantages will be apparent from the following description of one illustrative embodiment of the invention when considered in connection with the accompanying drawings, in which:

40 Fig. 1 is a front elevation showing parts in open position;

Fig. 2 is a top plan view with parts in the same position as in Fig. 1;

Fig. 3 is a right side elevation with parts in 45 the same position;

Fig. 4 is a vertical section on the line 4—4 of Fig. 1;

Fig. 5 is a similar section with parts in closed position;

50 Fig. 6 is a vertical section on the line 6—6 of Fig. 1;

Fig. 7 is an enlarged view partly in rear elevation and partly in section of parts shown in the lower right hand corner of Fig. 2; and

55 Fig. 8 is an enlarged sectional view of a safety

device associated with the front edge of the material compressing apron, the view being taken on the line 8—8 of Fig. 4.

The apparatus in general comprises means for rolling the material into a compact cylindrical 60 roll, means for holding a container in position to receive the roll of material, means for ejecting the roll of material from the rolling means into the container and ancillary mechanism for securing properly timed and coordinated action of 65 the various parts and for avoiding injury to the working mechanism and the person of the attendant operator.

The working mechanism of the apparatus is principally supported, as shown in the several 70 views and particularly in Figs. 1 and 2, upon vertical side frames 20, 22, intermediate vertical frames 24, 26 and, as seen at the left of the figures, a horizontal frame 28 supported at its left end upon a pedestal 30 and at its right end upon 75 the side frame 20. The vertical frames may be connected by transverse beams, bolts or the like as required.

The means herein shown for rolling the material into a cylindrical roll and for confining it 80 during this operation comprises, as best shown in Figs. 1 and 4, parallel end plates 32, 34 attached to the upper interior sides of the intermediate frames 24, 26 respectively and between the parallel plates 32, 34 a flexible apron 36 attached at one end to a horizontal trough-like bar 85 38 supported at its ends upon the frames 24, 26 and partially concentric with the circumferential edges of openings 40, 42 formed in the parallel end plates 32, 34 respectively.

The other or travelling end of the apron is attached to a transverse bar 44 movable between the end plates 32, 34, the bar being carried upon ears 46, which, in turn, are operatively borne upon guide rods 50, 52 attached, as best shown 95 in Fig. 3 to the stems of T-links 54 of a pair of endless carriers in the form of chains 56.

Each chain passes in several stretches, starting upward from the bottom left corner of Fig. 3, over a plurality of spaced guide sheaves R1, R2, 100 R3, R4, R5, R6, R7 and R8, beneath an adjusting sheave R9, and thence over a large sprocket 60 keyed to a drive shaft 62 supported in suitable bearings in the vertical frame members. All of the sheaves R1 to R9 inclusive are supported 105 on the outer sides of the intermediate frames 24, 26 and the adjusting sheaves R9 are mounted upon axles 57 fixed in hubs 58a of plate brackets 58 formed with slots 58b and held upon the frames by cap screws 59.

The guide sheaves are so arranged that the chains passing over them move the travelling end of the apron carried thereby in a generally curved path at the top of the machine and bring it down in a substantially straight path at the front of the machine. Thus the apron is caused, while changing from its open position, as shown in Fig. 4, where it forms a material-receiving hopper, to its closed position, as shown in Fig. 5, 10 where it forms a constricting cylinder, to bear upon the front curved edge of the trough-like bar 38. The chains 56 are driven first in one direction and then in the reverse direction, thus successively carrying the travelling end of the 15 apron from the position of Fig. 4 to that of Fig. 5 and back to initial position for one complete operation.

For the purpose of avoiding buckling of the 20 apron as well as for securing smoother and closer disposition thereof against the curved front edge of the bar 38, the apron 36 as seen in Fig. 1 is made of a plurality of overlapping sheets. These sheets 36a, 36b, 36c overlap interiorly from left to right, thereby insuring that the material which 25 is forced from left to right during ejection from the closed apron will not catch in the overlapping joints.

In addition to the above mentioned arrangement of guide rollers intended to secure constant 30 contact of the apron while moving past the front edge of the bar 38 there are (Fig. 2) a plurality of chains 64a, 64b, 64c—one for each of the apron sheets 36a, 36b, 36c—attached at their front ends (Figs. 4 and 5) to the apron bar 44 and at their 35 rear ends to a weight 66 carried by anti-friction end rollers 68 riding upon an inclined track 70.

Near the top of the machine the chains 64a, 40 64b, 64c pass over guide pulleys 72 carried by a shaft 74 and when the travelling end of the apron with the attached chains is carried down past the front of the trough-like bar 38 as shown in Fig. 5, the chains also press each of the sheets of the apron against the bar 38 to prevent material within the apron from escaping. The position of the shaft 74 is such that the chains 45 passing over the pulleys thereon will press the apron sheets tightly against the bar 38 but will not bend in the upper side of the apron sufficiently to cause it to come in the path of an 50 ejecting device moving through the closed up apron.

Equalized pressure on each of the three sheets of the apron is secured by having each of the chains adjustably connected with the weight 66, 55 as shown for one of the chains in Fig. 5, through a headed rod 76 engaging a spring 78 housed within a recess in the weight 66.

Thus with the above described arrangement, 60 the unanchored or free moving end of the apron 36 attached to the bar 44 may be positioned as shown in Figure 4, to form a hopper. As the bar 44 moves downwardly with the chain 56 to a position in front of the trough-like bar 38 (at the left-hand side of the trough-like bar 38 as 65 shown in Figure 4) the flexible apron 36 is positioned to form a relatively large cylinder. Further downward movement of the bar 44 gradually draws and forces the apron 36 over the front curved edge of the trough-like bar 38 (the left-hand edge of the bar as shown in Figure 4) and 70 reduces the size of the cylinder formed by the apron 36 and the trough-like bar 38, as shown in Figure 5. As the steel wool or like compressible material, which is placed in the apron 36 75 when it is in its hopper-like position, (Figure 4),

is compressed by the compressing action of the cylinder formed by the apron 36, the pressure required to compress the steel wool is increased. As the apron 36 reaches the position shown in Figure 5, the compressing action becomes greater, and the pressure with which the apron 36 is held against the front or left-hand edge of the bar 38 is also increased. As a result of this co-action between the trough-like bar 38, the apron 36, and the material being compressed, a tight 85 positive seal is established between the apron 36 and the front edge of the trough-like bar 38, whereby the material being compressed is positively prevented from escaping between the apron 90 36 and the front edge of the bar 38. This positive seal effected between the apron 36 and the trough-like member or bar 38, is in addition to the force which the chains 64a, 64b and 64c exert upon the individual sheets of the apron 36.

The drive shaft 62 may be operated by any 95 suitable gearing. Referring to Fig. 1 and the lower left hand portion of Fig. 2, the gearing comprises a pinion 63 fast on the shaft 62, the pinion being in mesh with and driven by a reciprocating rack bar 80. The rack bar bears on 100 its side a wrist pin 82 attached to a connecting rod 83 actuated by a crank pin 85 protruding from the face of a gear 84 fast on a stub shaft 86 rotatably mounted in a bearing in the side frame 20. The gear 84 of the stub shaft 86, in 105 turn, is driven by a pinion 87 fast on a main shaft 88. The main shaft 88 at its other end carries a gear 89 in mesh with a pinion 91 on a lay shaft 92. The lay shaft 92 also carries a gear 93 in mesh with a pinion 95 on the shaft 94 110 of a motor M. The reciprocating rack bar 80 at its front end may conveniently be held upon the drive shaft pinion 63 by a stud supported roller 79 and at its rear end (see also Fig. 4) may be guided by other stud supported rollers 81. 115

From the foregoing description it is clear that the rack bar 80 has a motion which follows a sine curve—and that the motion of the sprocket 60 and the transverse bar 44 (which is moved by the sprocket 60 through the medium of the chains 120 56) also has a motion which follows a sine curve. Further, this motion which is imparted to the transverse bar 44, and by which the apron 36 is bent into a compressing cylinder, has many advantages, among which are the following: At 125 about the point where the transverse bar 44 first forms the apron 36 into a closed cylinder, it has its maximum speed, and accordingly, the material in the apron is compressed at a maximum rate. As the movement of the bar 44 continues, 130 its speed becomes slower (following a sine curve), but at the same time the force available for moving the bar 44 is correspondingly increased—thus, as resistance to the compressing of the material increases, the rate of compression decreases 135 but the force available for the compression increases.

This operation is highly advantageous—for among other things, it reduces the strain, and wear and tear on the apron 36, by applying the maximum compressing force at a minimum speed.

The container into which the compacted material is deposited may be of any usual open-ended type but the container chosen for illustration is formed as a sleeve open at both ends. 140 When received these sleeves are creased longitudinally in two lines so as to lie flat. On the extreme right of Fig. 1 a stack of such flat sleeves C is shown disposed upon a frame supported table 100 within convenient reach of an 145 150

operator. The sleeves thus constructed are adapted to be opened by hand, and since the material of which their sides are formed is light may be pressed into a generally circular shape.

- 5 The means herein provided for holding a container in position for the insertion of compacted material ejected from the rolled up apron through the opening 42, comprises, as best shown at the right of Fig. 1, the left of Fig. 3 and in Fig. 7 a cup 102 attached to the outer side of intermediate frame 26 in proper position for a bottom opening 103 of the cup to coincide with the opening 42 in the end plate 34, which latter opening, as previously explained, is in line with the similar opening 40 and the constricted cylindrical interior space of the apron when the apron is rolled up, as shown in Fig. 5. The cup 102 at its outer open end is formed with an annular conical flange 104 for guiding one end of the sleeve C (indicated in dotted lines in Figs. 1 and 7) into the interior of the cup. At its bottom around the opening 103 the cup is formed with an annular groove 106 adapted to receive the sleeve and impart to it a generally circular shape.
- 20 The outer end of the sleeve C is adapted to embrace the conical plug 108 of a swinging clamp block 110 pivotally supported at its upper edge upon depending brackets 112 fastened beneath the table 100. The clamp block 110 is normally urged to a retracted position, as shown in full lines in Fig. 7, by a coil spring 113 attached to tabs 114 and 115 on the block and table respectively.

For swinging the clamp block into container-engaging position (as shown in dotted lines in Figs. 1 and 7) it is provided with a hand latch 116 reciprocably supported (Fig. 3) within apertured lugs 117 on the rear face of the clamp block, the latch between the lugs being formed with an enlarged portion 118 engaged and urged to the left by a spring 119 pressing at its other end against one of the lugs 117.

As viewed in Fig. 7, the right end of the latch is slidably received within the arcuate slot 120 of a latch plate 121 secured to the rear edge of the table 100. The rear end of the hand latch 116 is provided with a ring 122 fixed in non-slidable relation thereon, the ring being of greater diameter than the width of the upper portion of the slot so as normally to ride upon the side edges of the slot. The slot at its lower end, however, is formed with an enlargement 120a of sufficient size to receive the ring 122 and, consequently, when the operator moves the clamp block 110 from the full line position of Fig. 7 to the dotted line position and into holding relation with the end of a sleeve, the enlarged ring on the end of the latch drops into the enlarged portion of the slot—the latch being urged to the left by spring 119 pressure—and holds the block securely in position until such time as the operator pushes upon the latch to release it from the slot. When this occurs the block under urge of the spring 113 moves back to its full line position, releasing the sleeve which in the meantime has been supplied with a roll of compacted material.

The means herein provided for ejecting a roll of compressed material from the coiled apron, comprises, as may be seen in Fig. 1, a horizontal plunger 124 held by guides 126, 127 rising from the horizontal frame 28 in line with the openings 40 and 42. The rear end of the plunger may be attached as by a clip 128a to a link chain 128 passing over guide sheaves 129 loosely mounted upon pins 133 protruding from the front of

the horizontal frame 28. The outer end of the chain 128 is attached to the outer end of a weighted arm 130 pivoted upon the right pin 133 while the inner end of the chain is attached a second chain 132 operating in a plane at right angles to the plane of the first chain. The chain 132 near the base of the machine passes over a guide sheave 134 loosely mounted upon a stud 135 affixed to the side of the frame 20 and is attached at its rear end as may be observed in Fig. 6 to the periphery of an oscillating winding disc 136.

Oscillation of the disc 136 thus provides reciprocation of the chains 132 and 128 to move plunger 124 through the coiled-up apron 36 and openings 40, 42 to eject compacted material into a sleeve held in position between the cup 102 and the clamp block 110, as previously described.

Referring to the left of Fig. 2 and Fig. 6, the disc 136 is rotatably but non-slidably mounted upon the main shaft 88 adjacent the left end of that shaft which is carried in an upright bearing bracket 90. To the right of the disc a notched clutch sleeve 140 is slidably mounted upon a squared portion 88a of the shaft 88 and is adapted to engage with the similarly notched hub 137 of the winding disc 136 to cause the disc to be rotated at intervals with the shaft.

The clutch sleeve 140 may be operated by a clutch lever 142 the bifurcated end 143 of which embraces the sleeve and carries facing pins 144 operating within an annular groove 141 of the sleeve. The clutch lever 142 may be pivoted upon a fixed vertical pin 146 so as to oscillate between the full and dotted line positions shown in Fig. 2, while moving the clutch sleeve into and out of engaging position. The end of the clutch lever nearest the front of the machine is pivotally connected to a magnet lever 150 pivotally supported upon a fixed vertical pin 152 and engaged at its front end by the plunger 154 of a magnetic solenoid S.

If the solenoid S is energized for a short interval the front end of the lever 150 will be moved to the left, as viewed in Fig. 2, thereby moving the front end of the clutch lever 142 to the right and correspondingly moving the bifurcated end 143 of the clutch lever together with the clutch sleeve 140 to the left into clutch engaging position. The clutch sleeve tends to remain in this position even though the solenoid be de-energized. When this occurs shaft 88 will rotate the winding disc 136 clockwise (as viewed in Fig. 6) to wind up the chain 132 and move the plunger 124 on its instroke, i. e., to the right as viewed in Fig. 1. When the disc has rotated sufficiently to cause the plunger to move completely through the apron and eject the material the disc 136 acting through a face cam 138 which comes into engagement with the clutch return roller 145 mounted on the clutch lever 142, moves the clutch sleeve into disengaged position. As soon as the disc 136 is disengaged from the main shaft 88 the weighted arm 130 attached to the end of the chains 128, 132 connected with the disc causes the disc to be returned to the position shown in Fig. 6.

The clutch operating solenoid S may be controlled by any suitable mechanism capable of effecting its energization in properly timed relationship with the operation of the apron. Referring to the left of Fig. 2 and the right of Figs. 4 and 5 the side frame 20 near the rear of the machine above the stub shaft 86 adjustably supports a slotted strap 158 formed with a lateral

pin 159 pivotally attached to one end of a tubular mercury switch 156. The free end of the tubular switch 156 has a pin 160 adapted to ride upon the periphery of a cam plate 162 fixed to the outer end of the constantly driven stub shaft 86.

Normally (Fig. 4) the switch pin 160 rides upon a circular portion 162a of the cam plate 162, during which period the switch is open; but periodically—when apron 36 is closed—(Fig. 5) the pin 160 rides up upon the raised cam portion 162b of the plate to cause the switch to be closed and through suitable electrical conductors to energize the solenoid S. Shortly thereafter, the pin 160 rides down the other side of the cam portion 162b allowing the switch to open again and de-energize the solenoid. Adjustment of the slotted strap 158 along the frame 20 varies the position of the switch 156 and changes the time at which it is actuated by the cam plate, thus making it possible to coordinate the movements of the switch and magnet controlled plunger 124 very closely with the movements of the apron.

Since the plunger 124 and related parts operate quite rapidly and have considerable inertia it is desirable to cushion their movements in order to avoid objectionable vibration and excessive wear.

As seen at extreme left hand portion of Fig. 1, the parts on the in-stroke of the plunger 124 are cushioned by a buffer comprising a slideable rod 166 movable through vertical guides 31 on the pedestal 30, the rod being normally supported by a rigid collar 168 at its upper end and moved against the action of a surrounding spring 170 by a second collar 172 arranged for direct engagement by the forked end 131 of the weighted arm 130.

On the out-stroke, as seen at the extreme left of Fig. 1, the plunger 124 may be cushioned directly by a resilient bumper 123 mounted in an abutment 125 rigidly attached upon the left end of the horizontal frame 28.

Additionally, on the out-stroke of the plunger 124 the parts may be cushioned (Fig. 6) by a buffer comprising a slideable rod 176 movable through horizontal guides 177 on the base of the bearing bracket 90, the rod being urged to the left by a surrounding spring 180 acting against the left guide 177 and a collar 178 on the rod. The rod between the guides 177 is also provided with a member 182 adapted to be engaged by the spaced lugs 139 of the winding disc 136. In Fig. 6, the lugs 139 and collar 182 are shown in engaging position.

The means for safeguarding the machine against breakage and for protecting the person of the operator, as best shown at the top of Fig. 1, the bottom of Fig. 2, and the upper left hand portion of Fig. 3, comprises a horizontal circuit-breaker bar 184 carried by insulating blocks 186. The outer sides of the blocks 186 are equipped with stud-borne rollers 188 riding upon tracks 190 attached to and spaced from frames 24, 26 by overhanging brackets 192, the blocks being held in position to travel ahead of the apron 36 at all times by arms 194 attached to the apron-moving T-links 54 of chains 56 previously described.

Referring to Fig. 8 the bar 184 comprises a metallic rod 183 and a shorter insulating sleeve 185 for the rod. The blocks 186 are slotted on one side to receive the bare ends of the rod 183 and these ends are normally urged into contact with sockets 196 by springs 197 acting upon the rod through insulating bearing pieces 198.

The rod 183 thus forms an electrical connection in series with the flexible conductors 200 attached

to the sockets 196 but the connection is adapted to be broken in case the bar 184 meets with an obstruction, such, for example, as the arm of the operator if not withdrawn in time or any other rigid part extending across the top of the trough-like bar 38.

The breaking of the circuit in this manner may be employed in numerous ways to effect stoppage of the machine before the travelling end of the apron positioned behind the circuit-breaker bar arrives at the obstruction. As shown at the top of Fig. 3 the flexible conductors 200 pass over fixed pulleys 202 and movable weighted pulleys 204 to provide free movement of their lower travelling ends and at least one of the conductors may extend (see right side of Fig. 3 and upper right corner of Fig. 2) to a relay box 206 carrying parts for controlling the motor M and the solenoid 207 of a mechanically-gripping electrically-releasing brake 208 provided for the motor shaft 94. Also extending from the relay box 206 toward the front of the machine is a conduit 210 carrying conductors to a manual control switch 212. The manual control switch, however, is incapable of starting the motor while the circuit-breaker bar 184 is displaced from either of the sockets 196.

In operation, the switch 212 is actuated to supply current to the motor and the solenoid 207 of the electro-mechanical brake 208, causing release of the brake and starting of the motor and parts driven thereby. When started the machine is allowed to continue in operation as long as desired. Assuming that the parts in operation have attained the positions in which they are shown in all the figures save Fig. 5, the operator places a quantity of loose material in the hopper formed by the apron 36. He then takes in his left hand a sleeve C from the pile of flat sleeves on the table 100 and by pressing on the edges partially opens it, places one end in the cup 102 and swings the clamp block 110 down to secure the other end of the sleeve. When the block 110 is pulled down the ring 122 on the end of the hand-latch 116 drops into the enlarged portion 120a of the arcuate slot 120 and holds the clamp block in place. Continued operation of the machine brings the apron into the position shown in Fig. 5 where the travelling end is shown to have been drawn downwardly near the floor at the front of the machine and the body of the apron forms with the trough-like bar 38 an open ended cylinder somewhat smaller than and in line with the openings 40 and 42 in the end plates 34 to compress the material into a compact roll of a size adapted to pass through the opening 42 into the container C.

At this point the clutch controlling mercury switch 156 is closed by the cam portion 162b of the constantly rotating cam plate 162 coming beneath the pin 160 on the free end of the mercury switch 156 to tilt the switch up thereby momentarily closing the circuit energizing the clutch operating solenoid S. This causes intermesh of the clutch sleeve 140 and the hub 137 of the winding disc 136 connecting the disc to the constantly rotating main shaft 83 to wind up the chains 132, 140 128 causing the plunger 124 to move through the cylinder formed by the apron and the openings at the ends thereof to push the compacted roll of material out of the cylinder and into the sleeve C.

Near the end of this in-stroke, movement of the plunger and related parts will be cushioned by engagement of the end of the weighted arm 130 with its associated buffer. Shortly thereafter the parts will return to withdrawn position, the face cam 138 on the winding disc 136 having meantime

disconnected the disc 136 from the shaft 88, allowing the weighted arm 130 to function for this purpose. The return movement of the plunger is cushioned by the bumper 123 and the winding disc 5 by the interaction of its peripheral lugs 139 and the associated buffer.

To remove the filled sleeve the operator pushes in on the latch rod 116 to release the ring 122 from the slot 120 whereupon the spring 113 returns the 10 block 110 to its retracted (full line) position.

If during these movements the circuit-breaker bar, travelling ahead of the end of the apron, should meet with an obstruction the current is cut off from the motor M and the solenoid 207 of the 15 brake 208 to quickly stop the machine before any damage can be done.

While one embodiment of the invention has been described with some particularity, it will be apparent that other embodiments and modifications 20 may be made within the spirit of the appended claims.

What is claimed is:

1. Apparatus for packaging steel wool or like material comprising end plates with aligned openings, a trough-like bar secured between the end plates adjacent the openings, a flexible apron including a plurality of sheets attached at one end to said bar, the sides of the apron fitting between said end plates, a rod attached to the other end 30 of the apron for imparting travel to it to wind up the apron upon the bar, the apron when wound forming with said bar an open-ended cylinder aligned with said end plate openings, a plurality of chains attached to the travelling end of said apron and pressing upon the surface of the apron 35 to hold it against the bar after the said travelling end passes the bar, each of said chains being attached to a weight and having independent relative movement therewith, and a plunger moving 40 through the cylinder formed by the rolled-up apron.

2. Apparatus for packaging steel wool or like material comprising parallel end plates with aligned openings, a trough-like bar forming a 45 parti-cylinder in line with said openings, a flexible apron attached at one end to said bar and forming in retracted position a hopper between said end plates and in closed position forming with said bar a cylinder aligned with said openings, and an 50 ejecting plunger moving through said openings and the formed cylinder.

3. Apparatus for packaging steel wool or like material comprising parallel end plates with aligned openings, a trough-like bar forming a 55 parti-cylinder in line with said openings, a flexible apron attached at one end to said bar and forming in retracted position a hopper between said end plates and in closed position forming with said bar a cylinder aligned with said openings, an ejecting plunger moving through said openings and the 60 formed cylinder, and means for securing coordinated movement of said plunger and apron.

4. Apparatus for packaging steel wool or like material comprising parallel end plates with 65 aligned openings, a trough-like bar forming a parti-cylinder in line with said openings, a flexible apron attached at one end to said bar and forming in retracted position a hopper between 70 said end plates and in closed position forming with said bar a cylinder aligned with said openings, an ejecting plunger moving through said openings and the formed cylinder, and means for securing coordinated movement of said plunger 75 and apron, said means comprising a magnet and

a cam controlled switch for governing the magnet.

5. Apparatus for packaging steel wool or like material comprising a flexible apron forming in one position a hopper for reception of material and in another position a constricted cylinder pressing the material into a roll, a reciprocable plunger movable through the formed cylinder for ejecting the roll, means for moving the apron between its two positions, and means timed with the apron moving means for actuating the plunger when the apron is formed into a cylinder. 80

6. Apparatus of the character described comprising a flexible apron adapted in retracted position to form a hopper and in closed position to form a constricting cylinder, means securing one end of said apron and means for causing travel of the other end of said apron about said first secured end, said means comprising an oscillating flexible member. 85

7. Apparatus of the character described comprising a flexible apron adapted in retracted position to form a hopper and in closed position to form a constricting cylinder, means securing one end of said apron and means for causing travel 100 of the other end of said apron, said means comprising an oscillating flexible member, and a reciprocatory rack bar for oscillating said flexible member.

8. Apparatus for packaging steel wool or like material comprising an apron adapted to be rolled up upon the material and including a plurality 105 of flexible over-lapping metal sheets.

9. Apparatus of the character described comprising an apron including a plurality of flexible 110 sheets adapted to be rolled up about a bar and a plurality of flexible members for pressing the sheets against the bar as rolled up.

10. Apparatus of the character described, comprising a flexible apron adapted to roll up upon a 115 bar to form a cylinder, one end of the apron being slidable past the edge of the bar, and means for pressing said apron against the edge of the bar, said means comprising a flexible member passing over a guide pulley on a fixed shaft, the 120 location of said pulley shaft being such that the flexible member constantly presses the apron upon the bar but does not bend in the apron-formed cylinder.

11. Apparatus of the character described comprising a constricting cylinder-forming mechanism, and means for holding a container adjacent one end of the formed cylinder, said means comprising a cup adapted to receive one end of the container and a hinged block adapted to 130 engage the other end of the container.

12. Apparatus of the character described comprising a constricting cylinder-forming mechanism, and means for holding a container adjacent one end of the formed cylinder, said means comprising a cup adapted to receive one end of the container and a hinged block adapted to engage the other end of the container, said block normally being urged into retracted position and provided with a latch for holding it into closed 140 container-engaging position.

13. Apparatus of the character described, comprising a constricting cylinder-forming mechanism, a plunger movable through said cylinder, means for operating said plunger comprising a 145 free disc on a constantly rotating shaft, a flexible member connected to said plunger and adapted to be wound upon said disc, a clutch sleeve splined to the shaft adapted to engage said disc and means for operating said sleeve comprising 150

- a magnet for throwing the sleeve into clutch engaging position and a cam on said disc for throwing it into disengaging position, and means for returning said disc and plunger to initial position 5 after the clutch is disengaged.
14. Apparatus of the character described comprising a constricting cylinder-forming mechanism, a plunger movable through the formed cylinder, means for operating said plunger comprising an oscillatory disc and a plunger-connected flexible member adapted to be wound upon said disc, means for turning said disc in direction to operate the plunger in ejecting direction, means to return the plunger and disc including a weight-10 ed arm, a buffer for said arm when moving in ejecting direction, and buffers for said plunger and disc when moving in return direction.
15. Apparatus of the character described comprising a rolling apron, a bar adjacent the path 20 of the travelling end of the apron, a motor driving said parts, and a member moving ahead of the travelling edge of the apron adapted to cause stoppage of the motor in case it meets an obstruction above the bar.
16. Apparatus of the character described, comprising a rolling apron, a bar adjacent the path of the travelling end of the apron, and means for causing stoppage of the apparatus in case the travelling apron end meets with an obstruction.
17. Apparatus of the character described, comprising a rolling apron, a bar adjacent the path of the travelling end of the apron, and means for causing stoppage of the apparatus in case the travelling apron end meets with an obstruction, 30 said means comprising a circuit breaker travelling ahead of the apron and a magnetic-mechanical brake adapted to quickly stop the apparatus when the circuit is broken.
18. In a machine for packaging attenuated material comprising means for pressing the material into a compact bundle, means for supporting a container, means for ejecting the bundle from the pressing means into the container, means for automatically actuating said pressing and ejecting 40 means successively, and means for automatically stopping the machine when said pressing means meets with an obstruction.
19. Apparatus for packaging steel wool or like material comprising a flexible apron, means for automatically positioning said apron to receive 50 said material and for automatically closing said apron to compress said material, means for holding a container, means for ejecting the compressed material from the apron into the container, and means for automatically operating said apron-actuating means and ejecting means successively.
20. Apparatus of the character described comprising a flexible resilient metal apron adapted 60 in retracted position to form a hopper and in a closed position to form a constricted cylinder, means for permanently securing one end of said apron, and traveling means for securing the other end of said apron, said traveling means being 65 adapted to travel about the other end of said apron whereby said apron is wound around said first-named means, said traveling means comprising an oscillating member.
21. In apparatus of the character described, 70 in combination, a trough-like member, a moving member, a flexible apron attached at one end to said trough-like member and at the other end to said moving member, and said moving member being adapted to move automatically around said trough-like member to draw said apron over
- said trough-like member to form a constricting cylinder.
22. In apparatus of the character described, in combination, a trough-like member, the trough having a relatively small diameter, a movable element, an apron attached at one end to said trough and at the other end to said movable element, whereby said apron may be drawn over said trough to form a relatively large cylinder reducible to a relatively small cylinder by extended movement of said movable element.
23. In apparatus of the character described, in combination, a stationary bar, a movable bar, an apron attached at one end to said stationary bar and at the other end to said movable bar and means for actuating said movable bar for drawing said apron over said stationary bar to form a relatively large cylinder and by extended movement of said movable bar to form a relatively small cylinder.
24. In apparatus for packaging steel wool or the like, in combination, a flexible resilient apron automatically movable means and a stationary means moving said apron to an open position whereby said apron forms a hopper, and for moving said apron to a closed position whereby said apron forms a constricting cylinder, the resiliency of said apron facilitating the return of the apron to its hopper position.
25. In apparatus of the character described, in combination, a supporting member, a flexible member attached at one end to said supporting member, a second supporting means; the other end of said flexible member attached to said second supporting means, said second supporting 105 means being adapted to pass the end of said flexible member attached thereto over said supporting member to form said flexible member into a constricting cylinder, and being adapted to force said flexible member against said supporting member as the cylinder formed by the flexible member is reduced in size.
26. In apparatus of the character described, in combination, a supporting member, a flexible member attached at one end to said supporting member, a supporting and guiding element, the other end of said flexible member attached to said supporting and guiding element, said supporting and guiding element being adapted to pass the end of said flexible member attached thereto 120 past said first-named supporting member to form said flexible member into a constricting cylinder, and being adapted to force said flexible member against said first-named supporting member as the cylinder formed by the flexible member is 125 reduced in size, and said force increasing as the size of the cylinder is reduced.
27. In apparatus for comprising a resilient compressible material, in combination, a trough-like element, a flexible member attached at one 135 end to said trough-like element, a supporting and guiding element, the other end of said flexible member attached to said supporting and guiding element, said supporting and guiding element being adapted to position said flexible member to form a hopper to receive said compressible material, and to pass one end of said flexible member over said trough-like member to form a constricting cylinder to compress said compressible material, and also to force the end 145 of said flexible member against said trough-like member, said force increasing as the constricting cylinder formed by said flexible member is reduced by further passage of said flexible member over said trough-like member.

28. In apparatus of the character described, in combination, a trough-like member, a movable member, a flexible apron attached at one end to said trough-like member and at the other end to said movable member, said movable member being adapted to move said apron over an edge of said trough-like member, whereby said apron and said trough-like member form a constricting cylinder, and means for pressing said apron against said edge. 10
29. In apparatus for compressing a resilient compressible material, in combination, a trough-like element, a flexible member attached at one end to said trough-like element, a supporting and guiding element, the other end of said flexible member attached to said supporting and guiding element; said supporting and guiding element being adapted to pass said flexible member over an edge of said trough-like member to form a substantially circular constricting cylinder with said trough-like member, and also to force said flexible member against said edge, said force increasing as the substantially circular constricting cylinder formed by said flexible member is reduced by further passage of said flexible member over said edge, but without deforming said cylinder. 20
30. In apparatus of the class described, in combination, a trough, a flexible apron having an end fastened within said trough, and means for mov- 25
- ing said apron over said trough, to form a cylinder reducible in size upon continued movement of said means. 35
31. In apparatus of the class described, in combination, a trough, a flexible apron having an end fastened within said trough, and means for moving said apron over said trough and said end to form a cylinder reducible in size upon continued movement of said means. 40
32. In apparatus of the class described, in combination, a resilient member, movable means for positioning said member to receive compressible material and for positioning said member to enwrap and compress said material, and means for actuating said movable means, said actuation increasing in effective actuating force as the resilient member approaches its final compressing position. 45
33. In apparatus for packaging resilient compressible material, in combination, a resilient member, means for positioning said member to receive said material, and for bending said member to enwrap and compress said material, and means for actuating said positioning means according to a sine curve motion, whereby said positioning means is moved with maximum speed during the initial stages of compression, and with minimum speed but maximum force during the final stages of compression. 50
